UNITED STATES PATENT OFFICE.

JOHN P. COLEMAN, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

1,238,887.

Specification of Letters Patent. Patented Sept. 4, 1917.

Application filed January 22, 1917. Serial No. 143,544.

To all whom it may concern:

Be it known that I, JOHN P. COLEMAN, a citizen of the United States, residing at Edgewood Borough, in the county of Allegheny and State of Pennsylvania, have invented certain new and useful Improvements in Railway-Traffic-Controlling Apparatus, of which the following is a specification.

10 My invention relates to railway traffic controlling apparatus, and particularly to apparatus for the control of fluid pressure actuated traffic controlling devices such as railway switches. More particularly, my invention relates to means for governing the 15 valves which in turn control the supply of fluid pressure to the motors which actuate such devices.

One object of the invention is the provision 20 of means responsive to reversals of current for governing the valves which control the supply of fluid pressure to the motor.

A further object of the invention is, primarily, to automatically arrest the flow of 25 energy to the switch operating mechanism the instant that such mechanism has fully responded to a previous action of its controlling lever to throw the switch, and, secondarily, to provide means essential to the 30 primary consideration which will insure immediate re-application of the energy should either the lever or the switch be moved out of coinciding positions. The primary consideration or feature is sought in order that 35 pressure losses may not exist in the switch mechanism when the latter is not actively engaged in moving a switch. The secondary feature is sought in order that attempts to operate a switch by means other than its

40 lever will cause energy to be restored to the operating mechanism to counteract such attempts. This latter provision being an emergency one and not called upon for activity in ordinary operation, is herein made 45 to embrace as its means of operation only such elements of control as are also essential elements in the ordinary operation of the switch by its lever, thus insuring that failures of the emergency provision will also 50 cause failure of the normal operating means.

I will describe certain forms of apparatus embodying my invention and will then point out the novel features thereof in claims.

In the accompanying drawings, Figure 1

is a view showing a railway switch having 55 applied thereto one form of operating and controlling mechanism embodying my invention. Fig. 2 is a view showing in horizontal section the valve and valve controlling apparatus C shown in Fig. 1. Fig. 3 is 60 a sectional view of a portion of the apparatus taken on the plane indicated by the line III—III in Fig. 2. Fig. 4 is a view showing a modified form of valve controlling apparatus which may be used in connection 65 with the mechanism shown in Fig. 1 and which embodies my invention.

Similar reference characters refer to similar parts in each of the views.

Referring first to Fig. 1, the reference character A designates a railway switch, which switch is operated by a fluid pressure motor B. This motor B is controlled by valve apparatus C, which apparatus will be hereinafter described.

The motor B, as here shown, comprises a cylinder 1, and a piston 5 adapted to reciprocate therein and to be moved in one direction or the other according as fluid pressure is admitted to the cylinder 1 at one end or 80 the other. The piston 5 is operatively connected with the rails of switch A through the medium of a suitable switch operating mechanism comprising, as here shown, a reciprocable bar 2 connected with the piston 5, 85 an alligator jaw 3 operated by a stud 6 on the bar 2 and a rod 4 operatively connected with the alligator jaw and also connected with the rails of the switch A. The structure and operation of a switch operating 90 mechanism of this type are so well understood in the art that further description and explanation are unnecessary.

Referring now to Figs. 2 and 3, wherein the valve apparatus C is illustrated in detail, 95 this apparatus comprises a valve body 7 provided with a valve chamber 8 in which is located a slide valve 9 adapted to reciprocate in suitable guides on a valve seat 10. The valve seat 10 is provided with three 100 ports 11, 12 and 13; the middle port 12 communicates directly with atmosphere, while ports 11 and 13 communicate with the left and right hand ends of cylinder 1 (Fig. 1) through the medium of pipes 11^a and 12^a, 105 respectively. The slide valve 9 is of the usual D-valve type, having a recess 18 (Fig. 3), so that when the valve is in one extreme posi-

tion, as shown in Fig. 3, it connects the right hand end of cylinder 1 with atmosphere and the left hand end with the valve chamber 8, whereas when the valve is in the other extreme position it connects the left hand end of cylinder 1 with atmosphere and the right hand end with chamber 8. Fluid pressure is at times admitted to chamber 8 by means which will be hereinafter explained.

10 The valve body 7 is provided with another chamber 14 to which fluid pressure, usually air, is constantly supplied from a suitable source through a pipe 15. Fluid pressure is at times supplied from chamber 14 to the 15 valve chamber 8 through a valve 16, which valve is biased to the closed position by a spring 17 and by the action of the fluid pressure in chamber 14 on the back of the valve. This valve is provided with a stem 20 16^a extending into chamber 8 and by means of which the valve may be opened at times, as will be hereinafter explained.

The valve body is provided with a cylinder 19 in which a piston 20 is adapted to 25 reciprocate. Fluid pressure is supplied to the cylinder 19 from chamber 8 through ports 21 and 21^a, and the supply of this fluid pressure is controlled by a valve 22, which valve in turn is governed by an electro-magnet 23, hereinafter termed the "lock magnet". The valve device 22 connects cylinder 19 with atmosphere through an opening 24, or with chamber 8, according as the lock magnet 23 is deenergized or energized. 35 An extension of piston 20 passes through a suitable hole in the valve body 7 and projects into the valve chamber 8, where it is operatively connected with a reciprocable plate 25, which plate moves transversely to 40 the direction of movement of the slide valve 9. This plate performs two functions, namely, to operate valve 16 and to mechanically lock the slide valve.

The function of locking the slide valve 45 is accomplished by the same means as that shown in United States Letters Patent No. 1,202,164, granted to John P. Coleman on October 24, 1916, this means briefly described comprising three upwardly projecting spaced transverse lugs on the upper surface of the slide valve and a tongue on the under surface of the plate 25, which tongue passes between the lugs on the slide valve and locks this valve when the piston 20 is 50 in the position in which it is shown in the drawing. The other function of this plate, namely, the opening of valve 16 is accomplished merely by the engagement of the plate with the stem 16^a attached to this 55 valve. The parts are so arranged that when the piston 20 is moved outwardly by the admission of fluid pressure to the cylinder 19, the slide valve 9 is unlocked and simultaneously the valve 16 is opened to admit fluid pressure to the valve chamber 8. The slide 60

valve 9 is reciprocated by a fluid pressure motor device comprising two axially aligned cylinders 26 and 26^a formed in the valve body 7 and in which are located pistons 27 and 27^a, respectively. Attached to piston 27 is a piston rod 28, and similarly attached to piston 27^a is a piston rod 28^a, which rods abut against opposite ends of the slide valve 9. It will be clear, therefore, that when the slide valve is unlocked 75 it may be reciprocated by alternately admitting fluid pressure to cylinders 26 and 26^a. The supply of fluid pressure to these cylinders is preferably taken from the valve chamber 8, although it may also be taken from chamber 14 in certain applications of the device. Cylinder 26 is connected with the chamber by ports 29 and 29^a, and the supply of the fluid pressure through these ports is controlled by a valve 30. Similarly, cylinder 26^a is supplied with fluid pressure by ports 31 and 31^a, and the supply of fluid pressure through these ports is controlled by a valve 32. Each valve 30 and 32 is biased by a spring 33 or 33^a to such 80 position that the corresponding cylinder is disconnected from the chamber 8 and is connected with atmosphere through a port 34 or 34^a. When either valve is operated to its other position against the action of its biasing spring the corresponding cylinder is disconnected from atmosphere and is connected with the valve chamber 8 so that fluid pressure is then admitted to such cylinder to cause operation of the slide valve 9. 85 90 95 100

In Fig. 2 I have for the sake of clearness shown the lock magnet 23, the valve 22 controlled thereby, and the valves 30 and 32, in the same plane as the remainder of the drawing, but in practice these parts are preferably swung around that they are vertically disposed with respect to the plane of Fig. 2.

The valves 30 and 32 are controlled by a polarized electromagnetic device P comprising, in the form here shown, a fixed U-shaped permanent magnet 35 and a movable member 37. The member 37 comprises a tongue 36 of magnetizable material, preferably soft iron, pivotally mounted at a point 36^a adjacent the middle of the bend in 110 the permanent magnet, which tongue carries at its outer end a pole-piece 36^b which engages with one pole or the other of the permanent magnet according as the tongue swings in one direction or the other. The 115 tongue 36 carries a winding 42 which is reversibly energized by means hereinafter explained, whereby the tongue will be caused to swing to one extreme position or the other depending on the direction of the current 120 flowing in the winding. The tongue 36 is operatively connected with the two valves 30 and 32 in such manner that one or the other of these valves will be reversed against the action of the biasing spring according 125 130

as the tongue is swung in one direction or the other. To accomplish this, the valves are provided with stems 41 and 41^a, respectively. Rocker arm 39 is pivotally connected, intermediate its ends, to a standard 38 forming part of the supporting frame for the valve apparatus, and rocker arm 39^a is pivotally connected in a similar manner to a standard 38^a. Each stem 41 and 41^a rests against the outer end of the corresponding rocker arm 39 or 39^a, while the inner end of each of these arms is operatively connected with the tongue 36 by a link 40 or 40^a. The arrangement of the links and rocker arms is such that when the tongue is in its extreme left hand position, as viewed in Fig. 2, the inner end of arm 39 is forced outwardly or away from the tongue so that the outer end of this arm 20 forces valve 30 inwardly against the action of its biasing spring 33; while at the same time rocker arm 39^a is permitted to swing in clockwise direction so that valve 32 occupies its normal position under the influence 25 of its biasing spring 33^a. Fluid pressure is then admitted to cylinder 26 (provided chamber 8 is connected with the source of fluid pressure) and cylinder 26^a is open to atmosphere. When, now, tongue 36 is reversed, rocker 39 is swung counter-clockwise to permit valve 30 to reverse under the influence of its biasing spring, and arm 39^a is swung also in counter-clockwise direction 30 to reverse valve 32 in opposition to its biasing spring. 35

The links 40 and 40^a are so connected to the tongue 39 and to the rocker arms that when either valve is positively operated against the action of its biasing spring the 40 pivotal points of the corresponding link 40 or 40^a and the pivotal point 36^a of the tongue are nearly in a straight line so that the pressure of the air on such positively operated valve and the action of the spring corresponding to such valve create only a very slight force on the tongue tending to drive the latter out of its corresponding extreme position. In other words, the links 40 and 40^a with the tongue 36 constitute two toggles 45 one or the other of which is nearly straightened out when the tongue occupies one extreme position or the other. By this construction I materially reduce the possibility of the force exerted by the valves reversing the tongue 36 in the event that the current in winding 42 fails, and the permanent flux of magnet 35 remains unassisted to hold the valve. 50

The outer end of each rocker arm 39 and 39^a is formed of a resilient member 43 or 43^a, the purpose of which is to allow the tongue 36 to swing to its extreme position in contact with one pole or the other of the permanent magnet in the event that the valve 55 which is positively operated by such move-

ment becomes fully reversed before the tongue reaches such extreme position. By this construction I avoid the possibility of an air gap between the tongue and the permanent magnet with the consequent reduction of the force with which the tongue 70 would be held to the permanent magnet.

In Fig. 2 I have shown one arrangement of circuits for the control of the magnet 23 and the winding 42 of the valve apparatus 75 by means of a controlling lever L. This lever L operates a contact 44 for the control of magnet 23, and it also operates contacts 45 and 45^a, constituting a pole-changer, for governing the direction of current in winding 42. This lever L is one of a plurality of similar levers comprised in an interlocking machine, and it is understood that in practice suitable indication apparatus would be provided for governing the movements of 80 lever L in accordance with the movements of the switch A, but in this view I have purposely omitted such indication apparatus and the circuits and contacts controlling the same in order to simplify the drawing, they 85 forming no part of the present invention.

The operation of the railway switch and its controlling apparatus may be described as follows:

When the switch A is in the extreme position in which it is shown in Fig. 1 and the lever L in Fig. 2 is in the corresponding extreme position in which it is shown in solid lines, magnet 23 is deenergized and winding 42 is energized from battery 46 in 95 such direction that the tongue 36 occupies its left hand position, as shown. Valve 30 is therefore in such position that cylinder 26 is connected with chamber 8 but chamber 8 is not connected with the source of fluid pressure because valve 22 is in such position that cylinder 19 is open to atmosphere. The slide valve 9 is, of course, locked in such position that the left hand end of cylinder 1 is connected with chamber 8 and the right 100 hand end is connected with atmosphere.

When it is desired to reverse the position of switch A, the controlling lever L is swung upwardly through a portion of its stroke until it is stopped by the indication apparatus (not shown) in such position that contact 44 engages fixed contact member 44^a, and contacts 45 and 45^a reverse the direction of the current in winding 42. The closure of contact 44-44^a energizes magnet 23 from 115 battery 46, thus actuating valve 22 to admit fluid pressure to cylinder 19 whereupon plate 25 is shifted to unlock the slide valve 9 and to open valve 16, thus admitting fluid pressure to chamber 8. The circuit for magnet 23 is from battery 46 through wire 51, contact 44-44^a, wire 52, magnet 23, wire 53 to battery 46. The circuit for winding 42 is from battery 46, through wire 47, contact 45^a, wire 49, winding 42, wire 48, contact 45, 120

125

wire 50 to battery 46. The reversal of the current in winding 42 causes the movable member 37 of the electromagnetic device P to shift to the right, thus reversing valves 30 and 32 so that cylinder 26 is now connected with atmosphere and cylinder 26^a is connected with chamber 8. Slide valve 9 is then shifted to its other extreme position so that the left hand end of cylinder 1 is connected with atmosphere and the right hand end is connected with chamber 8. The motor device B then actuates the switch operating mechanism to reverse the position of the switch A. When the movement of the switch 15 is completed and the switch has been properly locked, the lever L is released by the indication apparatus and its final movement may be completed, thus opening the circuit for magnet 23. The deenergization of this 20 magnet causes valve 22 to operate to disconnect cylinder 19 from the source of fluid pressure and connect this cylinder with atmosphere, whereupon plate 25 is returned to the position in which it is shown in Fig. 2, 25 by action of the pressure in chamber 8 upon piston 20; the valve 16 automatically closes, while the slide valve 9 is again locked and chamber 8 is disconnected from the source of fluid pressure.

30 The operation of the apparatus for movement of switch A in the opposite direction is similar to the operation just explained, and will be apparent without further remarks.

Referring now to Fig. 4, I have here 35 shown a modified form of polarized electromagnetic device P' for controlling the valves 30 and 32. This device comprises a U-shaped core 55 of magnetizable material, preferably soft iron, on the legs of which are 40 mounted the polarizing windings 42^a, 42^b. The tongue 54 is in this case a permanent magnet which is pivotally mounted at one end in the portion of the core 55 connecting the two legs, and the other end of which is 45 adapted to engage with one pole or the other of the core 55. It will be clear, therefore, that the tongue 54 will be caused to swing to one extreme position or the other, that is, to one pole or the other of the core, 50 depending on the direction of the current supplied to the windings 42^a. The control of the valves 30 and 32 by the tongue 54 is exactly the same as the control of the corresponding valves by the tongue 36 in Fig. 2. 55 The advantage of the form of electromagnetic device shown in Fig. 4 as compared with that shown in Fig. 2, is that in the form shown in Fig. 4 the polarizing winding is not on the movable member, so that this 60 member is not as heavy as the movable member in the form shown in Fig. 2, and flexible connections to the magnet's windings are not required.

In Fig. 4, I have also shown a modified 65 form of lock magnet 23^a, and a modified ar-

rangement of the circuit for the control of this magnet. The winding of this magnet 23^a is in two sections *a* and *b*, section *a* being connected with wire 49 and a segment 57^a of a circuit controller D, while section *b* is connected with wire 48 and a segment 57^b of the circuit controller D. This circuit controller also comprises a movable contact member 56 which is operatively connected with the slide bar 2 in Fig. 1 in such manner that when this slide bar occupies either extreme position the contact member 56 engages with segment 57^a or 57^b, but when the slide bar occupies an intermediate position, that is, while the switch is being moved, member 56 is in contact with both segments 57^a and 57^b so that the two sections of the winding of magnet 23^a are then connected through 56, with one pole of the battery 46. This permits the magnet to remain energized during operation of the switch and irrespective of whether the lever is shifted or not at such times to cause reversal of the switch.

The operation of the controlling circuits shown in Fig. 4, is as follows: When the parts are in the positions shown in the drawing, winding 42^a is energized in one direction from battery 46, but section *a* of the winding of magnet 23^a is disconnected from the battery and is consequently deenergized and both terminals of section *b* of this winding are connected with the upper terminal of battery 46 so that this section *b* is likewise deenergized. Magnet 23^a is therefore totally deenergized. When it is desired to reverse the position of the railway switch, the controlling lever L is swung upwardly through a portion of its stroke until it is stopped by the indication apparatus (not shown) in such position that the contacts 45 and 45^a reverse the direction of the current in winding 42^a. The terminal of winding section *b* which is connected with wire 48, is now connected with the lower terminal of battery 46 so that section *b* is energized and the lock 100 magnet is therefore energized to reverse the valve 22 (Fig. 2). As soon as the slide bar 2 of Fig. 1 begins to move, contact 56 of circuit controller D is moved to such position that it connects winding section *a* also 105 with the upper terminal of battery 46, but wire 49 is connected with the upper terminal of battery 46 in this position of the lever and hence winding *b* only remains energized from battery 46. The lock magnet 23^a is 110 thus fully energized by one section (*a*) or the other (*b*) during movement of the switch, whether the lever is on one side or the other of its central position—the position of the lever determining which coil. After the 115 movement of the railway switch is completed and the switch is locked, contact 56 passes off from segment 57^b and both terminals of winding section *a* of magnet 23^a are 120 then connected with the upper terminal of 125 battery 46. The lock magnet 23^a is 130

battery 46 so that this section is deenergized. Section *b* is, of course, disconnected from the battery so that magnet 23^a is again fully deenergized.

- 5 With the arrangement of lock magnet 23^a and the controlling circuit therefor shown in Fig. 4, I accomplish the control of this magnet with one less wire than with the form shown in Fig. 2. Furthermore, with 10 the form shown in Fig. 4, if the switch operating mechanism is disconnected from the control circuits and is reversed by hand and the mechanism is then again connected with the control circuits, the switch will automatically 15 be returned to its proper position in coincidence with the position of the controlling lever L, because one section or the other of the winding for the lock magnet 23^a will be energized so that valve 22 (Fig. 20 2) will be operated to cause the admission 20 of fluid pressure to valve chamber 8 and so cause the return of the railway switch to its proper position.

One feature of the valve controlling apparatus embodying my invention is that the two valves 30 and 32 are mechanically connected through the rocker arms 39 and 39^a and the movable member of the polarized electromagnetic device, so that these two 30 valves must always be in opposite positions; that is, with this construction it is impossible to have both of these valves in such positions that fluid pressure is admitted to both cylinders 26 and 26^a. This feature applies 35 to the form shown in Fig. 4, as well as to the form shown in Fig. 2, and the operating circuits shown in each form of the valve may be used indiscriminately with both.

In the second form of my invention (Fig. 40 4), but two wires are used for the control of the two shifting magnets and the lock magnet, as against three wires in the first form. The methods are interchangeable. In the first form the lock is deenergized by 45 action of the lever after indication is received. In the second form the switch automatically locks the valve (and cuts off the air) the instant its movement is completed and does not depend upon the final movement 50 of the lever by the operator, thus saving a wire in the control, and air pressure, by admitting only enough air to do the work—cutting it off the instant the work is done.

55 Although I have herein shown and described only two forms of railway traffic controlling apparatus embodying my invention, it is understood that various changes and modifications may be made therein 60 within the scope of the appended claims without departing from the spirit and scope of my invention.

Having thus described my invention, what I claim is:

- 65 1. In combination, a railway traffic con-

trolling device, a fluid pressure motor for operating said device, a valve for controlling the supply of fluid pressure to said motor, fluid pressure means for operating said valve, means for supplying fluid pressure to said first means to cause reverse operations of said valve, and polarized electromagnetic means for controlling said second means.

2. In combination, a railway traffic controlling device, a fluid pressure motor for operating said device, a valve for controlling the supply of fluid pressure to said motor, and polarized electromagnetic means for controlling said valve.

3. In combination, a railway traffic controlling device, a fluid pressure motor for operating said device, means for supplying fluid pressure to said motor to cause reverse movements of said device, and polarized electromagnetic means for controlling said means.

4. In combination, a railway traffic controlling device, a fluid pressure motor for operating said device, and polarized electromagnetic means for controlling the supply of fluid pressure to said motor to cause reverse movements of said device.

5. In combination, a railway traffic controlling device, a fluid pressure motor for operating said device, a valve for controlling the supply of fluid pressure to said motor, fluid pressure operated means for causing reverse movements of said valve, and polarized electromagnetic means for controlling the supply of fluid pressure to said first means.

6. In combination, a railway traffic controlling device, a fluid pressure motor for operating said device, electromagnetic means comprising a member responsive selectively to reversals of current therein, and two valves operatively connected with said member for controlling the supply of fluid pressure to said motor to cause movements of said device in one direction or the other.

7. In combination, a railway traffic controlling device, a fluid pressure motor for operating said device, two valves for controlling the supply of fluid pressure to said motor to cause reverse movements of said device, electromagnetic means comprising a member movable to one extreme position or another according as said means is energized in one direction or the other, and connections interposed between said member and said valves for positively operating one valve or the other according as said member moves in one direction or the other, said connections being resilient to permit the member to move to its extreme position in the event that the valve positively operated by such movement reaches its operated position before the stroke of said member is completed.

8. In combination, a railway traffic con-

trolling device, a fluid pressure motor for operating said device, two valves for controlling the supply of fluid pressure to said motor to cause reverse operations of said device, each valve being biased to one controlling position, electromagnetic means comprising a member movable to one extreme position or another according as said means is energized in one direction or the other, and connections interposed between said member and said valves for operating one valve or the other in opposition to its bias according as said member moves in one direction or the other, the connection to each valve including a toggle device which is nearly straightened out when the corresponding valve has been operated by said member, whereby such valve then exerts very slight force tending to move the member away from its corresponding extreme position.

9. In combination, a fluid pressure motor device, two valves for controlling the supply of fluid pressure to said device to cause reverse movements thereof, electromagnetic means comprising a member movable to one extreme position or another according as said means is energized in one direction or the other, and connections interposed between said member and said valves for positively operating one valve or the other according as said member moves in one direction or the other, said connections being resilient to permit the member to move to its extreme position in the event that the valve positively operated by such movement reaches its operated position before the stroke of said member is completed.

10. In combination, a fluid pressure motor device, two valves for controlling the supply of fluid pressure to said device to cause reverse movements thereof, each valve being biased to one controlling position, electromagnetic means comprising a member movable to one extreme position or another according as said means is energized in one direction or the other, and connections interposed between said member and said valves for operating one valve or the other in opposition to its bias according as said member moves in one direction or the other, the connection to each valve including a toggle device which is nearly straightened out when the corresponding valve has been operated by said member, whereby such valve then exerts very slight force tending to move the member away from its corresponding extreme position.

11. In combination, a fluid pressure motor device, two valves for controlling the supply of fluid pressure to said device to cause reverse movements thereof, each valve being biased to one controlling position, a U-shaped permanent magnet, a magnetizable

tongue pivotally mounted adjacent the neutral portion of said magnet and having a pole-piece movable between the two poles of said magnet, a polarizing winding on said tongue, two rocker arms each pivotally mounted intermediate its ends, a stem for each valve in operative relation to the corresponding rocker arm on one side of the pivotal point thereof, and two links each pivotally connected with said tongue and with one of said rocker arms, the pivotal point of said tongue and the two pivotal points of one or the other of said links being nearly in a straight line when the tongue is in such extreme position that the valve corresponding to such link has been operated by said tongue whereby said valve exerts very little force on said tongue tending to move the latter out of such extreme position.

12. In combination, a railway traffic controlling device, a fluid pressure motor for operating said device, polarized electromagnetic means for controlling the supply of fluid pressure to said motor to cause reverse movements of said device, a controlling lever, and contacts and connections governed thereby for reversibly energizing said electromagnetic means.

13. In combination, a railway traffic controlling device, a fluid pressure motor for operating said device, a valve for controlling the supply of fluid pressure to said motor to cause reverse operations of said device, fluid pressure operated means for causing reverse movements of said valve, polarized electromagnetic means for controlling the supply of fluid pressure to said first means, a controlling lever, and contacts and connections controlled by said lever for reversibly energizing said electromagnetic means.

14. In combination, a railway traffic controlling device, a fluid pressure motor for operating said device, two valves for controlling the supply of fluid pressure to said motor to cause reverse movements of said device, electromagnetic means comprising a member selectively responsive to the direction in which said means is energized for governing said valves, a controlling lever, and contacts and connections controlled by said lever for reversibly energizing said electromagnetic means.

15. In combination, a fluid pressure motor device, two valves for controlling the supply of fluid pressure to said device to cause reverse movements thereof, each valve being biased to one controlling position, a U-shaped permanent magnet, a magnetizable tongue pivotally mounted adjacent the bend in said permanent magnet and movable between the poles of said magnet, a polarizing winding on said tongue, and means interposed between said tongue and said valves for operat-

ing one valve or the other in opposition to its bias according as said tongue is adjacent one pole or the other of said magnet.

16. In combination, a fluid pressure motor 5 device, two valves for controlling the supply of fluid pressure to said device to cause reverse movements thereof, each valve being biased to one controlling position, a U-shaped magnetizable core, a polarizing winding on 10 said core, a permanent magnet tongue pivotally mounted adjacent the bend in said core and movable between the poles of the core, and means interposed between said tongue and said valves for operating one valve or 15 the other in opposition to its bias according as said tongue is adjacent one pole or the other of said core.

17. In combination, a railway traffic controlling device, a fluid pressure motor for 20 controlling said device, a valve for controlling the supply of fluid pressure to said motor, means for locking said valve, a lock magnet for controlling said locking means, fluid pressure operated means for causing reverse movements of said valve, polarized 25 electromagnetic means for controlling the supply of fluid pressure to said valve operating means, a controlling lever, and contacts and connections controlled by said lever for 30 governing said lock magnet and for reversibly energizing said polarized electromagnetic means.

18. In combination, a railway traffic controlling device, a fluid pressure motor for 35 controlling said device, a valve for controlling the supply of fluid pressure to said motor, fluid pressure operated means for causing reverse movements of said valve, polarized electromagnetic means for controlling 40 the supply of fluid pressure to said valve-operating means, a source of current, a pole-changer for reversibly connecting said source with said polarized electromagnetic means, means for locking said valve, a lock 45 magnet for controlling said means, said lock magnet comprising two winding sections, and means operatively connected with said motor and coöperating with said pole-changer to deenergize both of said sections 50 when the motor and the pole-changer occupy corresponding extreme positions, to energize one section when the motor occupies either extreme position and the pole-changer is not in the corresponding position, and to energize both sections while the motor occupies 55 an intermediate position.

19. In combination, a fluid pressure motor, two electromagnetically controlled valves for causing reverse operations of said motor, 60 means for actuating said valves by current of one polarity to cause operation of the motor in one direction, and for actuating said valves by current of reverse polarity to cause a reverse operation of the motor.

20. In combination, a fluid pressure motor, two electromagnetically controlled valves for causing reverse operations of said motor, means for actuating said valves by current of one polarity to cause operation of the motor in one direction, and for actuating said valves by current of reverse polarity to cause a reverse operation of the motor, and a third electromagnetically controlled valve actuated by current of either polarity for controlling the supply of fluid 65 pressure to said first-mentioned valves.

21. In combination, a reversely operable fluid pressure motor, and electromagnetic means for causing operation of said motor in one direction by current of one polarity 80 and for causing reverse operation of the motor by current of reverse polarity.

22. In combination, a reversely operable fluid pressure motor, and electromagnetic means for causing operation of said motor 85 in one direction by current of one polarity and for causing reverse operation of the motor by current of reverse polarity, and electromagnetic means for controlling the supply of fluid pressure to said first-men- 90 tioned means.

23. In combination, a reversely operable fluid pressure motor, and electromagnetic means for causing operation of said motor in one direction by current of one polarity 95 and for causing reverse operation of the motor by current of reverse polarity, said means including magnetic means for preventing inadvertent movement of the motor when said first means is deprived of current. 100

24. In combination, a railway switch, a fluid pressure motor for moving said switch, electromagnetic means responsive to reversals of current for controlling said motor, a circuit for controlling said means, a lever 105 for causing reversals of current in said circuit whereby reverse movements of said motor are effected, and means controlled jointly by the lever and the motor for interrupting the supply of fluid pressure to 110 the motor when the motor and lever coincide in position.

25. In combination, a railway switch, a fluid pressure motor for moving said switch, electromagnetic means responsive to reversals of current for controlling said motor, a circuit for controlling said means, a lever for causing reversals of current in said circuit whereby reverse movements of said motor are effected, and means controlled jointly 115 by the lever and the motor for interrupting the supply of fluid pressure to the motor on completion of a movement of the motor in response to a movement of the lever. 120

26. In combination, a railway switch, a fluid pressure device for causing reverse movements of said switch, a lever for controlling said fluid pressure device, and

- means controlled jointly by said lever and said switch for admitting fluid pressure to said device only when the two do not coincide in position.
5. 27. In combination, a railway switch, a fluid pressure device for causing reverse movements of said switch, a lever for controlling said fluid pressure device, and means controlled jointly by said lever and said switch for cutting off the supply of fluid pressure from said device when the two coincide in position.
10. 28. In combination, a railway switch, a fluid pressure device for causing reverse movements of said switch, a lever for con-

trolling said fluid pressure device, and means controlled jointly by said lever and said switch for cutting off the supply of fluid pressure from said device when the two coincide in position and for admitting fluid pressure to said device to return the switch to the position corresponding to the lever position if the switch is moved away from such position by means other than the lever.

In testimony whereof I affix my signature 25
in presence of two witnesses.

JOHN P. COLEMAN.

Witnesses:

A. HERMAN WEGNER,
R. GEORGE RUDMAN.
